UNITED STATES PATENT OFFICE.

CHARLES HENRY DOMMETT, OF SWINDON, ENGLAND, ASSIGNOR TO FRANK SIDDALL,
OF DETROIT, MICHIGAN.

EXPANDING TAP.

Application filed July 2, 1920. Serial No. 393,678.

(GRANTED UNDER THE PROVISIONS OF THE ACT OF MARCH 3, 1921, 41 STAT. L., 1313.)

To all whom it may concern:

Be it known that I, CHARLES HENRY DOMMETT, a subject of the King of Great Britain, and a resident of Swindon, county of Wilts, 5 England, have invented certain new and useful Improvements in Expanding Taps (for which I have filed an application in England July 3, 1917, Patent No. 116,574), of which the following is a full, clear, concise, 10 and exact description, such as will enable others skilled in the art to which the invention relates to make and use the same, reference being made therein to the accompanying drawings, which form a part of this specification.

This invention relates to expanding taps, for screw cutting, of the type in which a plurality of die plates placed in a plurality of slots formed axialwise and radiating from 20 the centre of a holder, are expanded by a spindle moved axially therein, a spring being arranged to contract the die plates on the spindle being moved in the opposite direction.

25 It is usual in practice to use taps of this type to cut threads and to use what are termed solid taps to size up the hole to a fine limit of diameter, especially in the manufacture of explosive shells. On the withdrawal of the solid tap the friction is such as to cause considerable wear to the threads reducing its life considerably.

This invention has for its object the provision of means for adjusting the diameter 35 of a tap, of the type described, which is specially necessary, after the cutting edges have been re-ground, in order that a very fine limit in diameter, when required, can be obtained, thereby dispensing with the necessity 40 of using a solid tap.

According to this invention a floating spindle is provided with two truncated conical shaped members with their smaller diameters facing one another, each member 45 having slots and cam-shaped surfaces arranged axialwise on their surfaces for the expansion and contraction of the dies. One of the truncated conical shaped members is adjusted endwise for increasing or decreasing 50 the effective cutting diameter of the die plates.

In a modified form one truncated conical shaped member is fixed or formed on the end

of a spindle, means being provided for giving endwise adjustment to the spindle. 55

The end of the holder has an annular recess for the reception of a plurality of coiled springs each having two projecting ends. Each spring when placed in position, has each of its ends bearing on the side of separate dies to force them toward the truncated 60 conical shaped member, or members.

The invention is illustrated with the aid of the accompanying drawings, Figure 1 being a longitudinal section showing part of the 65 shank in elevation, also the handle and die plates. Figure 2 half plan and half section through line 2—2 of Figure 1.

Figure 3 inverted plan of the head of Figure 1 in the direction of the arrow C, when 70 the cover plate is removed.

Figure 4 elevation of the spindle with the truncated cone shaped members. Figure 5 half plan and half section through line 5—5 of Figure 4. 75

Figure 6 elevation and Figure 7 plan of one of the die plates.

Figure 8 sectional elevation of the tap when used with one truncated cone shaped member on the spindle. 80

Figure 12 plan of a portion of the handle showing the circular end. Figure 13 modification of the tap, illustrated by Figure 8, for use with a hand tool. 85

Figure 14 part elevation and section of a device for automatically moving the truncated cone shaped member, or members, into 90 position for the dies to be retracted.

Figure 15 plan of Figure 14.

The holder is in the form of a circular bar a having a head a' of increased diameter, while the end of the small or shank portion 95 is formed either in the shape of a square a^2 in cross section for the purpose of enabling the holder to be operated by an ordinary tool constructed for the purpose, or with a circular end to adapt it to be used in a machine. 100

The head a' of the holder has a circular recess a^3 axially in one end leading to near the base thereof, leaving a concentric wall a^4 . An annular recess a^5 is also formed in the concentric wall a^4 on the end of the head 105 leaving an inner concentric wall a^6 around

the central recess a^3 and the outer concentric wall a^4 around the annular recess a^5 . The central recess a^3 is carried beyond the end of the slots a^7 , while the annular recess 5 a^5 is carried down to a depth sufficient to enable coiled springs b to be inserted as hereinafter described. The inner concentric wall a^6 , i. e., between the central and annular recesses a^3 and a^5 , projects beyond the end of 10 the head, the latter being flat and at right angles to the axis of the holder. A hole a^9 is formed axially in the case of the central recess a^3 and connects to an elongated hole a^{10} on the shank a . The elongated hole a^{10} 15 has two parallel sides and is at right angles to the axis of the holder, and of sufficient length axialwise of the holder to enable the spindle carrying the truncated cone shaped members to be moved endwise.

20 In the end of the outer concentric wall a^4 of the head of the holder are four slots a^7 axialwise of the holder so that the cutting edges of the die plates c placed therein, would, as they wear on their face edges c' , 25 be spaced equal distances apart circumferentially. The length of each of the slots a^7 , axialwise, is equal to the length of each of the dies c . The bases of the slots a^7 are at right angles to the centre line of the holder, 30 each slot being carried through the inner concentric wall a^6 . A portion of the outer circumferential surface of the head is cut away at a^8 on the cutting side c' of each of the die plates c , for clearance purposes.

35 Each of the die plates c is of equal dimensions and rectangular in form, the outer wall formed in the usual way with teeth for screw cutting or chasing. The back wall of each die plate c recedes at an angle longitudinally 40 from each side of its centre, to fit the outer faces of the truncated cone shaped members, one longitudinal half c^3 of the back wall being formed with a concavity across it for the length of the die plate to enable it to contact with the circumferential surfaces of the 45 truncated cone shaped members d and d' , while the other half c^4 recedes at an angle to adapt it to contact with the inclined portions d^2 of the slots of each of the truncated 50 cone shaped members d and d' .

The members for expanding the die plates are in the form of two truncated cones d and d' with their smaller diameters facing each other. These truncated cone shaped members 55 are placed on the end of a spindle e , the inner truncated cone shaped member d being fixed and of greater length than the outer one d' and having a portion d^3 of its larger end cylindrical and adapted to be 60 guided by the end of the central recess a^3 , while the outer truncated cone shaped member d' is adapted to be moved endwise towards the inner truncated cone shaped member d by the action of a nut f working over 65 the screw threaded end of the spindle e . A

feather e^3 is fixed on the spindle for preventing the outer truncated cone shaped member d' from rotating thereon while permitting it to be moved endwise. A spring b^2 is placed on the spindle e between the two truncated cone shaped members d and d' to keep them apart. When it is desired to reduce the effective diameter of the dies by release of the nuts f and f' the resiliency of the spring b^2 ensures that the outer adjustable truncated cone shaped member d' shall follow them.

Each of the truncated cone shaped members d and d' has four slots formed lengthwise in its circumferential face, the base d^1 of each slot convex, to seat the concave back c^3 of the die plate c , and of a width to equal the width of the concave back portion c^3 of the die plate c , one side d^6 of the slot being parallel to the radius line while the other side d^2 of the slot is inclined outwards to the horizontal to agree with the angle of the receding edge on the back of the die plates c .

One end of the spindle e carrying the truncated cone shaped member d is enlarged as at e' , the diameter of which is less than that of the larger diameter d^3 of the inner truncated cone shaped member d and adapted to pass into the hole a^9 formed axially through the base of the central recess a^5 of the holder, a hole e^2 , screw threaded, being formed in the side of the spindle near its end.

One end of the handle g , for operating, is 90 of smaller diameter than the length of the elongated hole a^{10} axialwise of the holder, and has its screw threaded portion g' attached to the screw threaded hole e^2 in the side of the spindle e' .

One side face of each die plate c has a circular recess c^5 therein while the other has a slot c^6 for the purpose of receiving the protruding ends b' of a coiled spring b placed in the annular recess a^5 between the 100 die plates c , and adapted to contact them when the spindle is oscillated by means of the handle g , into the position for the back ends of the die plates to contact with the base of the recesses of the two truncated cone 110 shaped members d and d' .

The outer truncated cone shaped member d' is adjusted towards the inner truncated cone shaped member d by means of a nut f , and a check nut f' , working over the threaded portion of the 115 spindle e . The outer wall of the recess a^5 has grooves a^{12} formed axialwise with the holder to partially seat the coiled portion of the springs b . The arrangement of the coiled springs in an annular recess, with 120 their two ends in engagement with one side of each of the two adjacent die plates, ensures that if one or two of the springs should fail, and if the remainder have their 125 ends engaged with one side of each of the 130

die plates they will, on the reverse movement of the spindle, be retracted.

A cover plate h is provided for the outer end of the head a' of the holder, having a 5 circular recess h' therein of a diameter to equal the outer diameter of the inner concentric wall a^6 of the holder; the depth of the recess h' to equal the distance the inner concentric wall a^6 projects beyond the end of 10 the holder. The cover plate h is secured in position by means of screw threaded bolts or studs i . A hole h^2 is made through the centre of the base of the circular recess through which passes the nut f , when placed 15 in position on the spindle e , the inner or end face of the nut f abutting against the larger end of the outer truncated cone shaped member d' .

On the oscillation of the spindle, by means 20 of the handle g , the portion d^2 of the wall of the slots of the truncated cone shaped members d and d' , inclined outward to their bases, bears against the receding ends c^4 of the die plates c and forces them outwards 25 against the action of the coiled springs b until the concave portions e^3 are seated by the action of the coiled springs b against the circumferential wall of the truncated cone shaped members d and d' .

On the wearing of the teeth, on the die 30 plates c , for forming the screw threads, or on its being found necessary to increase or decrease the diameter over the die plates, the necessary adjustment is made by the nut f forcing the outer truncated cone shaped 35 member d' towards, or permitting it to be retracted from, the inner truncated cone shaped member d so that when the spindle e' is oscillated, by means of the handle g , the die plates c are forced outwards against the 40 action of the coiled springs b to the desired extent.

In the improved tap the combined spindle and truncated cone shaped members are free 45 to move axialwise within certain limits in order that the back edges of the die plates can adjust themselves to an even bearing in the base of the slots of the truncated cone shaped members so as to ensure the cutting 50 edges protruding the requisite distance beyond the circumferential surface of the head.

One of the truncated cone shaped members being adjustable on the spindle enables 55 the range of the tap to be varied within certain limits thereby allowing of fine adjustments.

In a modification the adjustment of the dies for use in a holder used with a hand 60 tool or on a machine can be made with a spindle having oscillating and longitudinal adjustments but with a single truncated cone shaped member as represented in Figure 8.

The single truncated cone shaped member 65 d is formed with slots similar to that de-

scribed for the two truncated cone shaped members, as shown in Figures 2, 4 and 5 of the drawings, with the exception of the length which is increased in order to contact with most, if not all, of the back surface of the dies c , which have a single instead of a double inclined surface c^7 , as indicated in Figure 8 of the drawings. The spindle e^6 is of one diameter from the end of the truncated cone shaped member d with the exception of its central portion e^7 which is of 70 smaller diameter to reduce frictional contact in the hole a^9 of the shank of the holder. The hole a^9 in the holder is extended, over that described for the tap with two truncated cone shaped members, to meet a hole a^{13} carried diametrically through the shank and at right angles thereto. A wedge shaped member o having one end circular and the other shaped to agree with the body portion 80 which has flat sides parallel to each other and top and bottom curved to the same radius as the circular end, is placed in position through the end of the hole a^{13} , made diametrically to the shank so that its inclined surface o' contacts with the inclined surface p of a bearing piece p' . The bearing piece p' is circular to fit and slide in the hole a^9 longitudinally of the shank and has one end p^2 slotted to form an incline p while the side walls fit over the sides o^2 of the central portion of the wedge shaped member, and its other end contacting with the end e^8 of the spindle. The sides of the bearing piece, 90 having the incline, fitting over the sides o^2 of the wedge shaped member prevents it from twisting when the spindle is partially rotated.

The inner or rear end e^8 of the spindle is square in cross section to make a working fit in the square hole g^3 in the boss g^2 on the end of the handle g . The boss g^2 on the end of the handle g is circular with a square hole g^3 axially through it. The shank of the holder has an elongated hole a^{14} at right angles to its axis connecting with the hole a^9 axialwise of the shank of the holder to admit of the boss of the handle passing into and seating itself in an enlargement a^{15} of the hole a^9 formed axialwise of the holder 100 for carrying the spindle. The length of the enlarged portion of the hole is such as to permit the boss g^2 of the handle g to be partially rotated without endwise movement.

The length of the square portion e^8 of the spindle e^6 is such as will enable the spindle to be adjusted in either direction in the hole g^3 in the boss of the handle within predetermined limits. The hole a^{14} in the shank of the holder is elongated in a horizontal plane at right angles to its axis, while its length axialwise is also such as to permit of the handle being oscillated.

The handle is formed in two parts; that portion having the boss g^2 with the square 110

hole g^3 is at one end of the bar while the other end portion has a flange g^4 around its circumference permitting of a sleeve g' being placed loosely over it, the extreme end portion of the bar being screw threaded at g^5 over which the other part of the handle g is placed.

Each end of the hole a^{13} made diametrically to the shank is screw threaded to receive screw threaded studs r and r' to adjust the wedge shaped member in order that the spindle may be forced in one direction to increase, and be moved by resilient means in the opposite direction to decrease the effective diameter of the cutting edges of the dies. The smaller end of the truncated cone shaped member d has a projecting pin e^9 secured thereto or formed thereon adapted to pass inside the coils of a spring s . The inside face of the cover plate h has its central portion closed, instead of open as previously described, and is formed with a circular recess h^3 to receive the coiled spring s , the purpose of the latter being to force the spindle towards the rear end of the holder when the dies have to be reset by the endwise movement of the spindle for a smaller diameter.

It will be seen that on the slackening of the left hand screwed nut r it gradually comes away from the centre of the shank of the holder, and the right hand screwed stud r' can be screwed into the shank forcing the wedge shaped member towards the left hand stud permitting the coiled spring s in the recess of the cover to force the spindle towards the back end of the holder thereby reducing the effective diameter of the cutting edges of the dies, and vice versa.

In the case of a hand driven tap—see Figure 13—the hole in the recess of the holder is carried at a reduced diameter through the shank, its outer portion screw threaded to receive a screw threaded stud r^2 which, when screwed into the hole, bears on the end of the spindle and forces it forward to expand the dies to increase the effective diameter; but when the screw stud r^2 is unscrewed, or partially withdrawn from the shank of the holder, the effective diameter of the dies is decreased by the action of the coiled spring s forcing the spindle towards the back end of the holder.

The shank is provided with a screw threaded hole, at right angles to its axis, to receive a screw threaded stud r^3 which, when tightened, prevents the stud r^2 in the end of the shank from working back during the time the tap is in use.

In the modification of the improved tap for use on a power driven machine, I place on the shank a device, which, when the tap has nearly reached the depth required to be threaded, will move the handle, and with it the spindle, for the truncated cone shaped

member, or members, to be placed in the position to permit of the die plates being retracted by the coil springs from their working positions to enable the tap to be withdrawn from the threaded hole. The device 70 comprises a circular sleeve h having a finger, or cam surface h^4 , projecting from one end, and adapted to slide endwise by gravity on the shank of the tap, when the latter is in a vertical position, and restrained from 75 rotating or oscillating on the shank by means of a key a^{11} arranged longitudinally and protruding from the circumference of the same, the outside of the sleeve screw threaded with a left hand thread. Over the 80 screwed portion of the sleeve is placed a collar h^2 having its interior surface screw threaded to adapt it to fit the threaded portion of the sleeve. The collar is split horizontally at h^9 for a portion of its circumference and is also split longitudinally and the ends on each side of the split portion are provided with an outwardly projecting flange h^5 having a hole in each, one flange h^5 having a screw threaded hole to receive 85 the shank h^6 of a bolt head h^7 which is threaded into it to draw the flanges together and tighten the collar on the sleeve. The lower end of the collar has an outwardly extending flange h^8 .

The flange of the finger or cam being inclined at the requisite angle so that when the die plates are extended and the tap about to be used to cut the threads in the walls of the hole of any article, the position of the automatic device would be such that on the tap reaching to near the depth to which the threads are required to be cut, the flange on the collar would be in contact with the article and during the remainder 100 of the endwise movement of the tap the device would gradually travel endwise in the holder until the inclined side of the cam or finger contacts with the sleeve or roller on the handle and moves the spindle so that the 105 truncated cone shaped member, or members, would be moved into position to enable the die plates to be retracted automatically by the coiled springs and the tap withdrawn from the hole in the article by an endwise 110 movement.

The split collar being screw threaded on the sleeve enables it to be adjusted to act with various depths of holes within reasonable limits.

A plurality of elongated holes h^8 can be made through the collar at its junction with the flange for the purpose of passing lubricant to the tap.

Having now particularly described and 125 ascertained the nature of my said invention and in what manner the same is to be performed, I declare that what I claim is:

1. In an expanding tap, the combination of a holder having radial slots and an axial 130

bore, die plates seated in said slots and movable radially therein, a spindle rotatable and axially movable in said bore, said spindle having a tapered portion with cam surfaces adapted to force said plates outwardly by rotation of said spindle, resilient means for retracting said plates upon reverse rotation of said spindle, and means for adjusting the spindle axially and retaining the same in its adjusted positions.

2. In an expanding tap, the combination of a holder having radial slots and an axial bore, die plates seated in said slots and movable radially therein, a spindle rotatable and axially movable in said bore, said spindle having a tapered portion with cam surfaces adapted to force said plates outwardly by rotation of said spindle, resilient means for retracting said plates upon reverse rotation of said spindle, and means for adjusting the spindle axially and retaining the same in its adjusted positions comprising transverse wedge means engaging the spindle and spring means operative in opposition thereto.

3. In an expanding tap, the combination of a holder having radial slots and an axial bore, die plates seated in said slots and movable radially therein, a spindle rotatable and axially movable in said bore, said spindle having a plurality of oppositely tapered portions with cam surfaces adapted to force said plates outwardly by rotation of said spindle, means for retracting said plates upon reverse rotation of said spindle, and means for adjusting said tapered portions to vary the effective diameter of the die plates.

4. A tap as set forth in claim 3 including resilient means inserted between said tapered portions, for the purpose described.

5. A tap as set forth in claim 1, the resilient retracting means comprising a plurality of springs seated in recesses in said holder and each spring having its opposite ends engaging adjacent die plates.

6. In an expanding tap, the combination of a holder having radial slots and an axial bore, die plates seated in said slots and movable radially therein, a spindle in said bore rotatable and axially movable therein, said spindle having on its periphery spaced cams tapered longitudinally of the spindle and adapted by partial rotation of the spindle to force said plates outwardly, springs in engagement with and adapted to retract the said plates, and means for positioning the spindle axially of the holder to determine thereby the effective diameter of the said die plates.

7. In an expanding tap, the combination of a holder having radial slots and an axial bore, die plates seated in said slots and radially movable therein, a spindle rotatably positioned in said bore, oppositely tapered

cams on said spindle adapted by partial rotation of said spindle to force said die plates outwardly and by axial adjustment to determine the effective diameter of said tap when expanded, and means for adjusting said cams axially of the holder.

8. In an expanding tap, the combination of a holder, die plates supported therein for radial movement, means for moving said plates outwardly to increase the effective diameter of said tap, and means operative after a predetermined working movement of said tap to engage said moving means and return the same positively to its original position thereby permitting the said plates to be retracted.

9. In an expanding tap, the combination of a holder, die plates supported therein for radial movement, a spindle adapted by partial rotation to move said plates outwardly, a handle on said spindle, and means adapted to engage with a fixed abutment after a predetermined working movement of said tap and operating upon said handle to move said spindle to a position permitting the die plates to be retracted.

10. In an expanding tap, the combination of a holder, die plates supported therein for radial movement, a spindle adapted by partial rotation to move said plates outwardly, and means adapted to engage with the work after a predetermined working movement of said tap to actuate said spindle to a position permitting the retraction of said plates comprising a device longitudinally movable on said holder but non-rotative relative thereto and cam means on said device adapted to engage a part fixed to said spindle to cause rotation thereof.

11. In an expanding tap comprising a holder, radially movable die plates, and expanding means therefor including a handle extending laterally from said holder and movable in one direction to expand the tap and in the opposite direction to permit retraction of the said plates, means for moving the handle in the last-mentioned direction comprising a sleeve longitudinally slideable but non-rotatable on said holder, the forward end of said sleeve engageable with the work and the rear end having means adapted to actuate said handle.

12. In an expanding tool, the combination of a holder, dies radially movable therein, a central spindle, cam devices actuated by rotative movement of said spindle to force said dies radially outward to determine thereby the working diameter of said tool, and means carried by said spindle and adjustable relatively thereto to vary the initial position of said dies.

In testimony whereof I affix my signature.

CHARLES HENRY DOMMETT.
